Atty.

UNITED STATES PATENT OFFICE.

ALBERT E. FRIEDRICH, OF BERLIN-FRIEDENAU, GERMANY.

GRINDING MACHINE FOR SAFETY-RAZOR BLADES.

Application filed December 12, 1921, Serial No. 521,877, and in Germany December 16, 1920.

The present invention relates to a grinding machine for safety razor blades of the double-edged type, and the invention has for its object to provide a machine performing the grinding operation with perfect uniformity on all four sides of the blade.

A further object of the invention is to secure the blade being lifted from the grinding rollers at the moment when the direction of rotation of the grinding rollers is reversed, any injury to the surface of the grinding rollers being thereby avoided.

The present invention is illustrated on the drawing,

Fig. 1 showing, in end-elevation, one construction of the invention,

Fig. 2 a longitudinal section of the device,

Fig. 3 the same viewed from the other end,

Fig. 4 a longitudinal section of a somewhat modified construction,

Fig. 5 a longitudinal section of a third construction.

The apparatus is enclosed in a casing of suitable shape and size and constructed of any material suitable for the purpose. In the casing there is provided a partition 2 and a cover 3 between which two grinding rollers 4 and 5 are journaled, and a roller 12 adapted to hold the blade and its holder.

The grinding rollers as well as the holding roller 12 receive their motion from a drive shaft 11 journaled in the said partition 2 and the end wall 1, the said shaft being adapted to be turned in either direction by means of a crank 19. On the shaft 11 there is loosely mounted a gear wheel 14 engaging another gear wheel 13 provided on the holding roller 12 and, besides, there is firmly attached another larger drive gear 10 engaging the pinion 8 on the shaft 6 of the roller 4 as well as the gear wheel 9 on the shaft 7 of the roller 5.

It is preferable to make the gear wheel 13 relatively small, as the time consumed in swinging the blade from one grinding position into the other one will thereby be reduced.

The motion is transmitted to this gear wheel 14 by means of a friction coupling and, by the provision of the coupling on the driving shaft 11, any axial or radial forces acting on the blade shaft, as in the heretofore commonly used grinding machines, will be avoided. Hereby the shafts will become very easy running in their bearings in the walls 2 and 3, and they will pre-

serve a constantly favorable position relatively to the rollers.

The two grinding rollers 4 and 5 will receive, through the gear wheels 10, 8 and 9 a rotary motion in one or the other direction, depending on the handle 19 being turned to one or the other side.

As mentioned above, the gear-wheel 14 is loose on the shaft 11, and is pressed between a ring 15 resting against the fixed gear wheel 10 and a dish shaped friction disc 16 firmly attached to the shaft 11 by means of a nut 17 and a lock nut 18.

The friction disc 16 is held pressed against the gear wheel 14 by a certain pressure and, consequently, tends to turn the gear wheel and, thereby, the holding roller in the same direction as the grinding rollers 4 and 5, and if no blade is inserted in the holding roller 12, all three parts will revolve, but when a blade is inserted, the friction of the disc 16 against the wheel 14 will cause one edge of the blade to be pressed against the top face of one of the rollers, and the other edge against the bottom face of the other roller, both of the rollers being free to rotate in consequence of the power transmission from the gear wheel 10.

If the shaft 11 is rotated in the opposite direction the safety razor blade will immediately be turned out from the one grinding position, and swing over into the other grinding position in otherwise known manner.

As the friction between the disc 16 and the wheel 14 is always the same, whether the shaft 11 be turned in one or the other direction, it will be seen that the grinding pressure, i. e. the pressure which the blade exerts on the rollers, will always be the same and, at the same time, the blade will at once be lifted from the rollers, when the direction of motion is reversed, so that the blade cannot possibly damage the rollers.

The shaft 11 may be turned first for some time in one and then for some time in the other direction, or the handle 19 may be moved back and forth.

The coupling 16 may be constructed in various manners. For instance, as shown on Fig. 4, the wheel 14 may be fastened to the friction disc 16, which then co-operates with a fixed disc 17 provided on the shaft 11.

On Fig. 5 a third construction is shown. Here the gear wheels 13 and 14 are omitted, and instead thereof the blade shaft supports a flat friction disc 18, which co-operates

with the two friction discs 14^a and 14^b provided on the shaft 11 and, as shown on the drawing, engaging the periphery of the disc 13^a.

5 Opposite the portion of the disc 14^a which co-operates with the disc 13^a, there is provided between the two discs 14^a and 14^b a projection 14^c serving to secure the friction between the said two discs and the intervening disc 13^a.

By this construction a very intense and very uniform frictional pressure may be exerted on the knife roller.

In connection with the foregoing attention 15 is directed to the fact that the partition 2 divides the casing into two chambers in one of which the grinding and blade holding 20 rollers are arranged while in the other forward and small chamber the transmission mechanism is mounted. In other words all 19 of the parts with the exception of the handle are contained in the casing.

Having now described my invention, what I claim as new and desire to secure by Letters Patent is:

1. In a sharpener for double edged razor blades, a pair of grinding rollers, a pinion secured to each of said grinding rollers, a

blade-holding roller mounted between said grinding rollers, a drive shaft parallel to and spaced from said rollers, a drive gear fixed to said drive shaft and adapted to engage said pinions, a crank on said drive shaft adapted to be turned in either direction to actuate said drive gear, a friction disk secured to said blade-holding roller, and a pair of disks mounted on said drive shaft for frictionally engaging both faces of said friction disk.

2. A sharpener for razor blades, comprising a casing, a drive shaft mounted in said casing, a crank on said drive shaft, a pair of grinding rollers mounted in said casing, a blade-holding roller mounted between said grinding rollers, a friction disk secured to said blade-holding roller, a drive gear fixed to said drive shaft, pinions secured to said grinding rollers and adapted to mesh with said drive gear, a pair of discs mounted on said drive shaft and adapted to frictionally engage both faces of said friction disk to thereby press the blade against the grinding rollers while the drive shaft is being rotated.

In testimony whereof I affix my signature.

ALBERT E. FRIEDRICH.
